WALL WASHER

William J. Dunlap, Long Beach, Calif.

Application September 30, 1936, Serial No. 103,343

3 Claims. (Cl. 166—20)

This invention relates to a wall washer designed to be used in conjunction with deep well pumps.

An object of the invention is to provide a device that may be used in association with deep well pumps wherein the hydro-static weight of liquid being pumped, such as oil, in the well tubing, may be utilized to create a spray to spray the walls of the well at the producing formation. 5 It frequently occurs that the pores in the producing formation become plugged or stopped up due to the presence of heavy asphaltum or paraffin in the oil. By means of the present invention the walls may be sprayed tending to 10 keep these pores open.

Another object of the invention is to provide a combined valve seat and flow-bean.

A still further object of the invention is to provide a combined wall washer, gas separator and sand trap wherein the sand trap will be 20 automatically dumped so that the device is susceptible of being used in very sandy wells.

With the foregoing and other objects in view which will be made manifest in the following detailed description and specifically pointed out in 25 the appended claims, reference is had to the accompanying drawing for an illustrative embodiment of the invention, wherein:

Fig. 1 is a vertical section through the improved wall washer, gas separator and sand trap.

Fig. 2a is a partial view in vertical section illustrating a portion of Fig. 1 on an enlarged scale.

Fig. 2b is a partial view in vertical section illustrating the balance of Fig. 1 on an enlarged scale.

Fig. 3 is a horizontal section taken substantially upon the line 3—3 of Fig. 2a to illustrate the construction of the valve seat and combined flow-bean.

Fig. 4 is a horizontal section taken substantially upon the line 4—4 upon Fig. 2a.

Fig. 5 is a horizontal section taken substantially upon the line 5—5 upon Fig. 2b.

Fig. 6 is a perspective view of one of the spray beans or nozzles.

Referring to the accompanying drawing wherein similar reference characters designate similar parts throughout, 10 designates a coupling member enabling the device to be attached to the bottom of the working barrel of a deep well pump (not shown). This coupling member 10 is in turn connected to a coupling 11 which receives a combined valve seat and flow-bean, the bean portion of which is indicated at 12 and has

a vertical central passage therethrough of reduced diameter. At the top of the combined valve seat and flow-bean there is formed a seating surface indicated at 13 for the reception of a ball valve 14 retained within a cage 15. The seating surface 13 is provided with a plurality of radial grooves 16 so that in effect the seat for ball 14 is designed to leak. In other words, when the ball is seated, the groove 16 will not be closed thereby but will permit a small quantity 10 of fluid above the ball 14 to drain back therethrough. Coupling 11 has connected thereto an outer tube 17 and an inner tube or mosquito-bill 18. In the outer tube 17 there are a plurality of drilled and tapped holes arranged in 15 staggered relation to each other. In each hole there is screwed a very small bean or spray nozzle, such as those indicated at 19. Each bean or spray nozzle has a bore therethrough which is very fine, preferably made by a very fine drill. 20 The external semi-circular lips 20 may be used to facilitate screwing these beans into the drilled and tapped holes. The outer tube 17 in turn is connected to a lower coupling 21 which provides a seat for a ball 22 retained within a cage 23. The construction of this seat is intended 25 to conform to conventional practice so that when ball 22 is seated it forms a perfect closure through coupling 21. This coupling in turn suspends an outer tube 24 and an inner tube or mosquito-bill 25. In the outer tube there are formed 30 one or more upper apertures 26 and one or more lower apertures 27. The lower apertures are intended to form entrances for the oil and such 35 gas and sand as may be present. The upper apertures 26 are intended to afford gas outlets, it being understood that when the mixture of oil and gas enters the inlets 27 and flows downwardly around mosquito-bill 25, the gas tends to separate and may pass out of the outer tube 24 through the upper apertures 26. The outer tube 24 has connected thereto a coupling 28 which has a downwardly disposed valve seat 29 which is normally closed by a ball 30. Coupling 28 has suspended therefrom a round-nosed plug or bottom member 31 having a central aperture 32 at its bottom and side apertures 33 near its top. Coupling 28 also suspends a cap 34 having apertures 35 in registration or alignment with apertures 33. The bottom 40 of this cap is perforated as indicated at 36 and the cap is designed to receive a spring 37 urging a pin 38 upwardly against ball 30 to hold it in closed position. The pin extends through a spider 39. In the bottom of the cap there is an 45 50 55

adjusting screw 40 which may be adjusted to vary the compression of spring 37.

The operation and advantages of the improved construction are as follows: Upon the upward stroke of the plunger of the deep well pump not shown, oil and gas is drawn into tube 24 through apertures 27. The gas separates and may flow out through apertures 26. The oil and sand that is present, if any, passes downwardly, the oil entering the mosquito-bill 25. The sand tends to collect within coupling 28 on top of the ball 30 and when a sufficient amount of sand collects on the ball, its weight depresses the ball so that the sand is discharged through apertures 35 and 33. Perforations 36 keep the interior of the cap around the spring free so that the spring will readily function to allow the ball 30 to be depressed by the weight of the sand. Aperture 32 provides for egress of sand that may not escape through apertures 33. The oil is drawn up through mosquito-bill 25 past ball valve 22 and is drawn through mosquito-bill 18 through bean 12 and past the ball valve 14. It will be understood that the deep well pump with which the device is used has its standing valve removed. In other words, ball 14 is intended to take the place of the conventional standing valve. Upon the downward stroke of the plunger during which the plunger valve is open, the entire weight of the column of fluid in the tubing above the plunger is transmitted directly to ball 14 and due to the presence of the groove 16, leakage back may take place under this high hydro-static pressure of the column of liquid in the tubing. The interior of outer tube 17 is thus subjected to high hydro-static pressure which is carried by cross ball valve 22. This results in jets of liquid being discharged at high velocity and under high pressure through the bores in beans 19. This effectively sprays the walls of the formation particularly due to the staggered relation of the beans. By raising or lowering the tubing the position of the beans 19 can be varied and by periodically shifting the tubing, the formation can be effectively sprayed through its entire height. It is not intended that any large portion of the fluid in the tubing drain back through groove 16 during each down stroke of the plunger, but that only a relatively small portion of the fluid lifted during each stroke shall thus drain back and be discharged through the beans 19. In this manner the major portion of the fluid lifted during each stroke of the plunger will be retained in the tubing and only a small portion allowed to escape back for spraying purposes.

It is not essential that the sand trap be used

on the bottom of the outer tube 24. Any other closure for the bottom of this tube such as the conventional bull plug may be used for this purpose if desired.

Various changes may be made in the details of the construction without departing from the spirit or scope of the invention as defined by the appended claims.

What is claimed is:

1. A wall washer comprising a tube attachable to a deep well pump, there being laterally directed openings formed in the tube, a downwardly closing check valve closing the bottom of said tube, there being an inner tube within said tube leading to the bottom of the pump and extending downwardly toward said check valve to a point beneath said laterally directed openings whereby upon downward strokes of the plunger of the pump a portion of the fluid elevated may return downwardly through the inner tube and be discharged in sprays laterally from said tube against the walls of the formation.

2. A wall washer comprising a tube attachable to a deep well pump, there being laterally directed openings formed in the tube, a downwardly closing check valve closing the bottom of said tube, there being an inner tube within said tube leading to the bottom of the pump and extending downwardly toward said check valve to a point beneath said laterally directed openings whereby upon downward strokes of the plunger of the pump a portion of the fluid elevated may return downwardly through the inner tube and be discharged in sprays laterally from said tube against the walls of the formation, there being a bean controlling the flow through the top of said inner tube.

3. A wall washer comprising a tube attachable to a deep well pump, there being laterally directed openings formed in the tube, a downwardly closing check valve closing the bottom of said tube, there being an inner tube within said tube leading to the bottom of the pump and extending downwardly toward said check valve to a point beneath said laterally directed openings whereby upon downward strokes of the plunger of the pump a portion of the fluid elevated may return downwardly through the inner tube and be discharged in sprays laterally from said tube against the walls of the formation, there being a bean controlling the flow through the top of said inner tube, the top of the bean being enlarged to form a seat, a ball on the seat and there being radial grooves in the seat to enable the return of the portion of fluid elevated.

WILLIAM J. DUNLAP.
